INVENTOR:
STEPHAN PODMAYER,
Stephan Podmayer,
His ATTORNEYS

UNITED STATES PATENT OFFICE.

STEPHAN PODMAYER, OF ST. LOUIS, MISSOURI.

SPRING CATCH FOR TRAVELING BAGS.

Application filed January 4, 1924. Serial No. 684,343.

To all whom it may concern:

Be it known that I, STEPHAN PODMAYER, a citizen of Czechoslovakia, and a resident of the city of St. Louis, in the State of Missouri, and who have declared my intention of becoming a citizen of the United States, have invented a certain new and useful Improvement in Spring Catches for Traveling Bags, of which the following is a specification.

My invention relates principally to spring catches or fasteners of the pivoted hook type particularly adapted for use in retaining the hinged frames of traveling bags and the like in closed or locked position. It has for its principal objects to provide a strong and durable self-locking catch that will prevent accidental opening of the bag, and to provide for ease and quickness of operation, compactness of design, and simplicity and cheapness of construction. The invention consists in the combination and arrangements of parts hereinafter described and claimed.

In the accompanying drawing, which forms part of this specification and wherein like symbols refer to like parts wherever they occur;

Fig. 1 is a perspective view of a portion of a traveling bag provided with spring catches embodying my invention;

Fig. 2 is an enlarged vertical longitudinal section taken through a catch and the portions of the bag-frame cooperating therewith; the catch being shown in its projected or locked position;

Fig. 3 is a view similar to Fig. 2, the catch being shown in its retracted position;

Fig. 4 is a view similar to Figs. 2 and 3, showing the retracted catch swung upward in its unlocked position;

Fig. 5 is a horizontal sectional view on the line 5-5 of Fig. 3 showing the underside of the latch plate; and

Fig. 6 is a vertical cross-section through the latch adjacent to the pivot therefor on the line 6-6 of Fig. 2.

Referring to the accompanying drawing, my invention is shown in connection with the folding bag-frame A of a traveling bag or the like B. The bag-frame A comprises two bail-shaped sections 7 and 8 that are secured to the edges of the opening or mouth

of the bag B and are pivotally secured together at their ends, as at 9. The two sections 7 and 8 of the folding bag-frame A are arranged to fold one over the other in the closed position of the frame. As shown in the drawing, the outer or upper section 7 of the folding bag-frame A is of angle-shaped cross-section and is bent substantially into the form of a bail. The inner or upper section 8 of the folding bag-frame is shown in the form of a strap which is disposed with its faces vertical and bent 60 edgewise into the form of a bail.

The spring catches C, which are alike in detail, are mounted on the outer section 7 of the folding bag-frame A near each end thereof. Each of these catches comprises a base plate 10 which rests on the lateral top flange of the outer section 7 of the folding bag-frame A and is provided at each end with depending tabs 11 that project through slots provided therefor in said lateral flange 75 and are bent laterally beneath the same whereby it is rigidly secured to said outer frame-section and constitutes in effect a part thereof. Mounted on the base plate 10 is a hollow push-member or block 12. This block is provided on its underside with depending pins 13 that project through slots 14 provided therefor in said base plate, thereby permitting limited sliding movement of the block thereon. The pins 13 have heads at their upper and lower ends whereby the push-block is slidably secured to the outer section of the folding bag-frame. The base plate 10 has a lug 15 struck therefrom on its underside that forms an abutment or stop for one end of a spring 16, whose opposite end is attached to one of the pins 13 that slidably connect the push-block 12 to the base plate 10 and thereby serves to yieldably hold the slide-block at 90 one end of its movement.

A plate 17 has one end hinged to the hollow slide-block 12 by means of a hinge pin 18. This hinge pin is disposed horizontally and extends transversely of the slide-block whereby the hinged plate 17 is adapted for vertical upward swinging movement on the slide-block 12. In the closed position of the latch, this hinged plate rests flatwise on top of the hollow slide-block and 100 has a latch arm 19 on its underside that

projects through registering slots 22 in the bag-frame sections 7 and 8, thereby preventing the lateral movement required to open the bag-frame sections. This latch arm 5 projects from the underside of the hinged plate and is preferably shown in the form of a curved hooked-end latch arm or bolt which works in a vertical slot 20 provided therefor in the base plate 10. This latch 10 arm is provided adjacent to its upper end with a notch 21 adapted to straddle the adjacent edge of the slot 20 in the base plate in projected position of said latch arm. The end of the latch arm is also provided with 15 a shouldered portion 23 adapted in the raised position of the hinged plate to abut against the underside of the base plate and thereby limit the upward movement of said hinged plate and prevent the withdrawal 20 of the hook from the slot in said base plate as well.

The hinged end portion of the hinged plate is provided with a hub portion 22, having a cam surface adapted to engage the 25 upper surface of the free end portion of a flap leaf spring 24 secured at one end to the underside of the hollow slide-block. This spring is notched or bifurcated to straddle the depending hooked-end latch arm or bolt 30 of the latch and is adapted to bear against the cam-shaped hub portion of the pivoted lever and thereby yieldably hold the same in its raised and lowered positions.

The latch is released by first sliding the 35 slide-block against the pressure of the spring 16 as far as the slot and pin connection between the slide-block and the base plate will permit. This action disengages the notch in the hooked-end latch arm from the slot provided therefor in the base plate, thereby 40 permitting the hinged plate to be swung upwardly a distance sufficient to permit the latch arm to be withdrawn from the registering slots in the bag-frame sections, thereby 45 permitting the bag to be opened. When it is desired to lock the bag-frame sections, the hinged plate is swung down into a horizontal position; whereupon, the spring 16 operates to slide the slide-block and the latch 50 arm pivoted thereon in a direction that will cause the notched portion of said arm to straddle the edge of the slot in the base plate and thereby prevent upward movement of said hinged plate.

55 My device is applicable to folding frames generally. It is self-locking and can be easily and quickly operated; and it serves to prevent accidental opening of the bag-frame in the event that the bag is roughly 60 handled or overcrowded.

The hereinbefore described device admits of considerable modification without departing from the invention; therefore, I do not wish to be limited to the precise details of 65 construction shown and described.

What I claim is:

1. A bag-frame catch comprising a base member adapted to be secured to the outer frame-section of a folding bag-frame and a bolt member mounted on said base member for vertical swinging and horizontal sliding movement in registering openings in said base member and the frame-sections of said bag-frame, said bolt member being adapted in one position of its sliding movement to engage said base member and thereby prevent swinging movement of the bolt member, and means for automatically sliding said bolt into such engaged position when said catch is closed. 70 75 80

2. A bag-frame catch comprising a base member adapted to be secured to the outer frame-section of a folding bag-frame and a latch arm mounted on said base member for vertical swinging and horizontal sliding movement in registering slots in said base member and the frame-section of said bag-frame, said latch arm having a notch therein adapted in one position of the sliding movement of the latch arm to straddle the adjacent edge of the slot in said base member and thereby prevent swinging movement of the latch arm, and means for shifting said latch arm to a position of its sliding movement adapted to bring the notch thereof into engagement with the edge of the slot in said base member when said catch is closed. 85 90 95 100

3. A bag-frame catch comprising a push-block adapted to be secured to the outer frame section of a folding bag-frame for horizontal sliding movement thereon, a plate hinged on said push-block for vertical swinging movement, said hinged plate having a latch arm depending therefrom adapted in the lowered position of said plate and in the closed position of said bag-frame to project through registering openings in the frame-sections thereof, said latch arm being adapted in one position of the sliding movement of said push-block to engage said bag-frame in a manner adapted to prevent swinging movement of the latch arm, and means operating in the lowered position of said hinged plate to shift said push-block to a position of its sliding movement adapted to bring the latch arm of the hinged plate into engagement with said bag-frame. 105 110 115 120

4. A bag-frame catch comprising a base member adapted to be secured to the outer frame-section of a folding bag-frame, a push-block mounted on said base member for horizontal sliding movement, a plate hinged on said push-block for vertical swinging movement, said hinged plate having a latch arm depending therefrom adapted in the lowered position of the plate and in the closed position of said bag-frame to project through registering slots in said base member and the frame-sections of said bag frame, 125 130

said latch arm having a notch therein adapted in one position of the sliding movement of said push-block to straddle the adjacent edge of the slot in said base member and thereby prevent swinging movement of the latch arm, and a spring operating in the closed position of the latch to shift said

push-block to a position adapted to bring the notch of said latch arm into engagement with the edge of the slot in said base member.

Signed at St. Louis, Missouri this 2nd day of January, 1923.

STEPHAN PODMAYER.
